EXTENSION SCAFFOLD JACK

George D. Freeman, Alvin, Ill.

Application October 26, 1953, Serial No. 388,205

1 Claim. (Cl. 304—29)

This invention relates to an extension scaffold jack and more specifically provides a scaffold to be employed in construction work wherein the scaffold may be vertically adjustable without removing the scaffold boards and the various materials usually disposed thereon.

An object of this invention is to provide an extension scaffold jack having a plurality of successively extendable frame members which are telescopic in relation to each other and including means for extending the frame, locking the frames in extended position and bracing the frames in their extended position.

A further object of this invention is to provide a novel rack and pinion lifting means wherein the rack is sectional wherein successive sections of the rack may be attached to the first section of the rack thereby extending successive frame members.

A further object of this invention is to provide an extension scaffold jack having a detachable section secured thereon and a plurality of extensible frames with each of the frames having alignable apertures therein and a locking pin extending therethrough for securing the frames in extended position.

Yet another object of this invention is to provide an extension scaffold jack which is simple in construction, sturdy and rugged in nature, efficient to operate and constructed of readily obtainable materials thereby lending itself to economic manufacture.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

Figure 1 is a side view of the extension scaffold jack of the invention in extended position with the uppermost member being a detachable extension;

Figure 2 is a longitudinal, vertical section taken substantially along the center line of the frame showing the details of the rack and pinion extension means;

Figure 3 is a transverse, top plan section taken substantially along section line 3—3 of Figure 1 showing the relationship of the rack and pinion lifting means;

Figure 4 is a side elevational view of the extension scaffold jack in collapsed position with the top extension removed therefrom;

Figure 5 is a detail perspective view showing one of the detachable sections of the rack;

Figure 6 is a detail top plan section taken substantially along section line 6—6 of Figure 4 showing details of the brace attaching means; and

Figure 7 is a detail section showing the projecting guide and the socket receiving portion of the uppermost extension which is detachable from the uppermost frame.

Referring now specifically to the drawings in general, it will be seen that the numeral 10 generally designates the extension scaffold jack of this invention generally comprising a lower frame member 12, a second frame member

2

14, a third or upper frame member 16 and a detachable extension frame member 18.

It will be seen that each of the frame members 12, 14, 16, and 18 is formed with a pair of vertical uprights and a pair of cross-braces 20 and 22 being connected to opposite end portions of the uprights of the frames by suitable screw threaded members 24 having an operating handle 26 thereon for ease of manipulation. The cross braces 20 and 22 are secured at point 28 where the braces cross over each other. Each of the uprights of the frame members 12, 14, 16 and 18 is tubular with the lowermost frame 12 having a base member 30 secured to the lower end of the tubular uprights forming a support and closure for the lower end of the uprights of the frame member 12.

As shown in Figure 1, the frame 16 includes a cross-member 32 connecting the upper ends of the vertical uprights of the frame members 16 and forming a support for scaffold boards or the like. As shown in Figure 7, the upper ends of the vertical uprights of the frame 16 are each provided with an upwardly extending rod 34 with an enlarged ball member 36 on the end thereof and it will be seen that the ball member 36 forms a guide and positioning means for the tubular uprights of the extension member 18 wherein the extension member or frame 18 may be removed from the upper frame member 16. A cross member 38 is secured between the upper ends of the vertical uprights of the extension frame 18 with the vertical uprights extending slightly beyond the cross-member wherein scaffold boards will be retained on the cross-member 38 in an obvious manner.

As will be seen in the drawings, the upper end of the vertical uprights of the lower frame member 12 and the intermediate frame member 14 and the lower ends of the upper frame member 16 and the intermediate frame member 14 are provided with apertures 40 which are alignable with each other when in their extended position and locking pins 42 are provided for insertion in the aligned apertures when the frames 16, 14 and 12 are in extended position, thereby locking the frames in such extended position. It will be understood that the brace members 20 and 22 on the frame member 14 may be removed, thereby permitting the uprights of the frame 14 to be telescoped into the uprights of the frame 12 as the uprights of the frame 14 are smaller than the uprights of the frame 12, and it will be further understood that the uprights of the frame member 16 may be telescoped into the uprights of the frame member 14 after removal of the brace members 20 and 22. The extension frame 18 may be removed and the device will be in its collapsed position, as shown in Figure 4.

It will be seen in the drawings that a projecting lug member 44 is rigidly secured to the side of one of the vertical uprights of the upper frame member 16, and a depending elongated member 46 is rigidly secured to the undersurface thereof and extends downwardly parallel to the vertical upright of the frame 16 in spaced relation thereto. It will be seen that the elongated member is provided with projecting teeth 48 along one side thereof and an aperture 50 is provided at its lower end for a purpose described hereinafter. It will be understood that the elongated member 46 with the teeth 48 thereon forms a rack.

A U-shaped bracket member 52 is secured adjacent the upper end of the vertical upright of the lower frame member 12 by suitable welding or the like and surrounding the elongated member 46. A spacer member 54 is secured to the outer circumference of the vertical upright of the frame 12 and includes a bearing portion 56 riding against the rear edge of the elongated member 46. A pinion gear 58 is journaled between the legs of the U-shaped member 52 on a suitable axle 60 with one end of the axle 60 projecting beyond the U-shaped member

52 and a handle 62 is secured to the projecting end of the axle 60. The pinion gear 58 includes teeth 64 which are in meshing engagement with the teeth 48 on the elongated rack 46. A gravity operated pawl 66 is pivotally secured to the inner side of one of the legs of the U-shaped member 52 adjacent the upper edge thereof and engaging the teeth 64 of the pinion gear 58 wherein the gear 58 may be rotated only upon disengagement of the pawl 66 from the teeth 54. It will be seen that the bearing surface 56 maintains the elongated rack 46 in correct position for meshing of the gears 48 and 64. As shown in Figure 1, a second section of rack, indicated by the numeral 68, may be secured to the rack member 46 by insertion of a suitable fastener 76 through the aperture 50 in the rack 46 and an aperture 72 in a projecting lug on the upper end of the section 68. The rack section 68 is provided with an aperture at the bottom end thereof for securing successive sections of elongated racks wherein each section is similar to the section 68, as shown in Figure 5, with each section having teeth 48 thereon. It will be understood that the successive frame members 16, 14 and the like may be extended by attaching successive sections of the rack to the lower end of the first rack section 46 wherein the device has a long range of adjustability.

The operation of the device will be readily understood. The extension scaffold jack 10 of this invention is in its normally collapsed position in Figure 4, and by releasing the gravity operated pawl 66, the frame member 16 may be moved upwardly by rotating the handle 62, thereby moving the rack 46 and the frame 16 upwardly. When the frame 16 reaches its uppermost position, pins 42 may be inserted through aligned apertures 40 in the bottom of the vertical uprights of the frame 16 and the top of the vertical uprights of the frame 14. The cross-braces 20 and 22 may then be secured to the remote end portions of the vertical uprights by the suitable screw fastening members 24. It will be seen that the cross-piece 32 may be used to support a scaffold board thereon. It will be understood that additional sections 68 may be attached to the original rack section 46 for extending the frames 16 and 14 to their uppermost vertical positions in an obvious manner. If a greater vertical height is required, the extension frame 18 may be positioned over the upper frame 16 with the tubular uprights of the extension 18 extending over the guide bar 36 and the extending shank 34 wherein the uprights of the frame 18 are in alignment with the frame 16 and supported thereon. The cross-member 38, like the cross-member 32, is adapted to hold a scaffold board thereon and it will be noted that both of the cross-members 32 and 38 are recessed below the upper ends of the vertical uprights of the frame members 16 and 18 wherein scaffold boards will be retained on the cross-members. Obviously, the device of this invention may be constructed of readily obtainable pipe or other tubular members wherein the device will be economically feasible and the device may be utilized without removing the scaffold boards and vertically adjustable without removing the scaffold boards and the usual material found thereon. This is especially useful in masonry

construction where there is usually a heavy load of building blocks, mortar or tools on the scaffold boards and it is desirable to adjust the scaffold boards vertically without removing the material on the boards. The locking pins 5 42 provide a locking means for securing the frames in fully extended position and the pawl member 66 provides a lock for securing the frames in any extended relation.

From the foregoing, the construction and operation 10 of the device will be readily understood and further explanation is believed to be unnecessary. However, since numerous modifications and changes will readily occur to those skilled in the art, it is not desired to limit the invention to the exact construction shown and described, 15 and accordingly, all suitable modifications and equivalents may be resorted to, falling within the scope of the appended claim.

What is claimed as new is as follows:

An extension scaffold jack comprising a pair of tubular 20 vertical uprights, brace means interconnecting said uprights, a plurality of tubular extensible members telescopically received in each of said tubular vertical uprights, a cross member rigidly connecting the upper ends of the upper pair of tubular extensible members, an extensible 25 rack member connected at one end to one of said uppermost pair of tubular extensible members and extending downwardly in spaced, parallel relationship thereto, a bracket extending from one of said tubular vertical uprights, guide means in said bracket for said rack member, 30 a gear journaled in said bracket and having teeth in meshing engagement with the teeth of said rack member, a handle attached to said gear for moving the rack and tubular extensible members upwardly with respect to the tubular vertical uprights, said extensible rack member 35 being provided with a plurality of detachable rack portions each suspended from a higher rack portion, each portion having a length substantially equal to the length of a single tubular extensible member, and removable lock pins in said tubular vertical uprights and the lowermost tubular extensible members for locking said tubular extensible members in upwardly moved position.
